(57) **CLAIM**

The ornamental design for an e-cigarette vaporizing cartridge, as shown and described.

DESCRIPTION

FIG. 1 is a front perspective view of an e-cigarette vaporizing cartridge, showing our new design;

FIG. 2 is a front elevation view thereof, the rear elevation view being a mirror image thereof;

FIG. 3 is a left side elevation view thereof, the right side elevation view being a mirror image thereof;

FIG. 4 is a top plan view thereof; and,

FIG. 5 is a reduced front elevation view of the e-cigarette vaporizing cartridge, shown in use.

The broken lines consisting of evenly-sized spaced lines in the drawings depict portions of the e-cigarette vaporizing cartridge that form no part of the claimed design, while the broken lines consisting of unevenly-sized dash-dot-dash lines in the drawings depict the boundary of the claimed invention and it is understood that the claim extends to the boundary that forms no part of the claimed design.
